TRAPPING TOOL OR SIMILAR ARTICLE

Ernest J. Wilcox, R.R., Montezuma, Iowa 50171

Filed July 7, 1967, Ser. No. 7,730

Term of patent 14 years

(Cl. D22—18)

FIG. 1 is a perspective view of a trapping tool, showing my new design;

FIG. 2 is a side elevational view thereof;

FIG. 3 is an end elevational view thereof taken along line 3—3 in FIG. 2;

FIG. 4 is an end elevational view thereof taken along line 4—4 in FIG. 2;

FIG. 5 is a bottom plan view of the tool as shown in FIG. 2; and

FIG. 6 is a side elevational view thereof as seen from the right of the tool in FIG. 4.

The essential features of the design reside in the solid line portions thereof.

The ornamental design for a trapping tool or similar article, substantially as shown and described.
